United States Patent

Des. 235,278

Patented June 3, 1975

235,278

COMBINED PAINT APPLICATOR AND ROLLER THEREFOR

Robert I. Janssen, 1160 Sibley Memorial Highway,
St. Paul, Minn. 55118

Filed Oct. 10, 1972, Ser. No. 296,234

Term of patent 14 years

Int. Cl. D8—05

U.S. Cl. D64—18

FIG. 1

FIG. 2**FIG. 3****FIG. 4****FIG. 5**

FIG. 1 is a perspective view showing one end and the top portion of my new design of a combined paint applicator and roller therefor;

FIG. 2 is a top plan view of the design shown in FIG. 1;

FIG. 3 is a front elevational view thereof;

FIG. 4 is a side elevational view thereof; and

FIG. 5 is a bottom plan view thereof.

I claim:

The ornamental design for a combined paint applicator and roller therefor, as shown.
